(57) **CLAIM**

The ornamental design for a brush with straight handle and back surface having seven dots, as shown and described.

DESCRIPTION

FIG. 1 is a top plan view of a brush with straight handle and back surface having seven dots showing my new design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a perspective view thereof.

The claimed brush with straight handle and back surface having seven dots is used for cleaning shoes and clothing. The broken line showing of a handle is included for the purpose of illustrating a portion of the brush that forms no part of the claimed design.
